DESIGN FOR A FOLDING BACK REST FRAME OR SIMILAR ARTICLE

Sonia D. Anderson, Philadelphia, Pa.

Application August 19, 1941, Serial No. 102,949

Term of patent 7 years

To all whom it may concern:

Be it known that I, Sonia D. Anderson, a citizen of the United States and residing at Philadelphia, in the county of Philadelphia and State of Pennsylvania, have invented a new, original, and ornamental Design for a Folding Back Rest Frame or Similar Article, of which the following is a specification, reference being had to the accompanying drawings, forming part thereof.

Fig. 1 is a perspective view of a folding back rest frame or similar article, showing my new design.

Fig. 2 is a top plan view thereof with the arms in extended position.

Fig. 3 is a similar view thereof with the arms in folded position.

I claim:

The ornamental design for a folding back rest frame or similar article, substantially as shown.

SONIA D. ANDERSON.
